UNITED STATES PATENT OFFICE.

HENRY LANGE, OF QUINCY, ILLINOIS.

DESIGN FOR A HEATING-STOVE CASING.

Application filed February 17, 1926. Serial No. 16,551. Term of patent 7 years.

To all whom it may concern:

Be it known that I, HENRY LANGE, a citizen of the United States, residing at Quincy, in the county of Adams and State of Illinois, have invented a new, original, and ornamental Design for Heating-Stove Casings, of which the following is a specification, reference being had to the accompanying drawing, forming part thereof.

The figure is a perspective view of a heating stove casing, showing my new design.

I claim:

The ornamental design for a heating-stove casing, as shown.

HENRY LANGE.
